UNITED STATES PATENT OFFICE

167,259

MIXER JAR OR THE LIKE

Harold Fox, Minneapolis, Minn.

Application August 7, 1950, Serial No. 11,655

Term of patent 7 years

(Cl. D44—1)

To all whom it may concern:

Be it known that I, Harold Fox, a citizen of the United States, residing at Minneapolis, in the county of Hennepin and State of Minnesota, have invented a new, original, and ornamental Design for a Mixer Jar or the like, of which the following is a specification, reference being had to the accompanying drawings, forming part thereof.

Referring to the drawings:

The sole figure of the drawing is an exploded perspective view of a mixer jar or the like, showing my new design, the side not shown being like the side shown, except that it is devoid of the pouring spout.

I claim:

The ornamental design for a mixer jar or the like, as shown and described.

HAROLD FOX.
